CLAIM

The ornamental design for a shoe sole, as shown and described.

DESCRIPTION

FIG. 1 is a bottom plan view of a shoe sole showing my new design, it being understood that the pattern is continuous over the broken away white areas;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof.
